UNITED STATES PATENT OFFICE

155,239

DESIGN FOR A MANICURIST HAND SUPPORT

William C. Smith, East Liverpool, Ohio

Application March 11, 1948, Serial No. 145,024

Term of patent 7 years

(Cl. D86—10)

To all whom it may concern:

Be it known that I, William C. Smith, a citizen of the United States, residing at East Liverpool, in the county of Columbiana and State of Ohio, have invented a new, original, and ornamental Design for a Manicurist Hand Support, of which the following is a specification, reference being had to the accompanying drawing, forming a part thereof.

I claim:

The ornamental design for a manicurist hand support, substantially as shown.

WILLIAM C. SMITH.
